UNITED STATES PATENT OFFICE.

W. F. QUINBY, OF STANTON, AND G. G. LOBDELL, OF WILMINGTON, DEL.

IMPROVEMENT IN CULTIVATING-MACHINES.

Specification forming part of Letters Patent No. 38,124, dated April 7, 1863.

To all whom it may concern:

Be it known that we, W. F. QUINBY, of Stanton, and GEORGE G. LOBDELL, of Wilmington, both in the county of New Castle, and State of Delaware, have invented a new and Improved Rotary Digger; and we do hereby declare that the following is a full, clear, and exact description of the same, reference being had to the accompanying drawings, forming a part of this specification, in which—

Figure 1 represents a longitudinal vertical section of our invention. Fig. 2 is a plan or top view of the same. Fig. 3 is a sectional front elevation of the guide-wheels.

Similar letters of reference in the three views indicate corresponding parts.

The object of this invention is to construct a rotary digging-machine which can be drawn along by horses or other draft-animals, or which may be propelled by a steam-engine placed on its frame, the digging-teeth being so arranged that they can also act as propelling-teeth whenever it is desired.

The invention consists in the arrangement of two digging-cylinders, the main cylinder being provided with teeth, which are attached to bars which are fixed, or they may be attached to bars which are made to oscillate, the position of which is regulated and governed by a cam which is secured to the axle of the cylinder, said axle being journaled in two levers suspended from a windlass in such a manner that the position of the cylinder can be regulated at pleasure, and the secondary cylinder being provided with a series of stationary pulverizing-teeth and journaled in two pendent levers which connect by means of ropes or chains with a windlass in such a manner that the position of the secondary or pulverizing cylinder can be adjusted as may be desired.

To enable others skilled in the art to make and use our invention, we will proceed to describe it with reference to the drawings.

A represents a strong substantial frame, made of timber or any other suitable material, and supported in the rear by a smoothing-roller, B, and in front by two guide-wheels, C. The axle of the smoothing-roller has its bearings in two arms, a, which are firmly secured to the longitudinal timbers of the frame. The guide-wheels C are secured to a common axle, d, which is attached by means of a pivot, e, to

the lower end of a vertical shaft, b, so that said wheels can adapt themselves to the inequalities of the ground over which the machine passes. The vertical shaft b has its bearings in two journal-boxes, d', which are firmly secured to the front end of the frame A, and a lever, e, which is firmly attached to the upper end of said shaft, serves to adjust the position of the guide-wheel and to steer the machine. When the machine is propelled by steam this lever will be connected to a suitable steering-wheel.

D is the main or digging cylinder, which consists of two disks, D', that rotate on a stationary axle, E. Said disks are connected by cross-bars f, and they form the bearings for oscillating bars g, to which the digging-teeth h are secured. The position of the oscillating bars g is regulated by arms i and a central cam, F. Whenever the teeth begin to descend as the disks revolve in the direction of the arrow marked thereon in Fig. 1 the loose ends of said arms sink down upon the surface of the cam F, and when the teeth cut into the ground said loose ends bear hard on the surface of the cam and prevent the teeth leaving the ground before they have cut through the desired distance. On passing the point of the cam the loose ends of the arms are released and the teeth, which by this time have left the ground, assume the position shown in Fig. 1. By the combined action of the arms i and cam F the digging-teeth scoop up the dirt and turn it over, thus imitating the action of digging by hand; or the cam and oscillating bars may be dispensed with and the teeth attached to a fixed bar, and the disks secured to the shaft, and so revolve with it.

The axle E of the digging-cylinder has its bearings in two levers, G, which are fulcrumed on pivots j, secured in the longitudinal timbers of the frame A, and the loose ends of these levers are suspended by means of ropes or chains k from a windlass, l, the axle of which has its bearings in two standards rising from the front part of the frame A. By rotating the windlass in the proper direction the ropes or chains wind up on the same, and the digging-cylinder is raised from the ground, and the depth to which the teeth cut can thus be regulated. The windlass l is retained in the desired position by a ratchet-wheel and pawl, or by any other desirable means. When it is desired to make the

teeth cut to their full capacity the levers G are fastened down by means of buttons m. One of the pins j, which form the fulcra for the levers G, rotates in its bearings, and a wheel, H, secured to the inner end of the same and gearing into a corresponding wheel, H', on the axle E of the digging-cylinder, imparts to said pin a rotary motion which is transmitted through the action of the gear I I' to the pulverizing-cylinder J. This cylinder has its bearings in pendent arms K, which are suspended from the ends of the pins j, so that the cylinder can be raised or lowered without throwing the wheels I I' out of gear. The wheels H H' I I' form friction-gears, so that in case of a sudden check of one of the cylinders, no part of the machine will suffer any injury.

The pulverizing-cylinder J is armed with several rows of cutters, n, and the gear-wheels H H' are speeded up, so that said cylinder rotates with sufficient velocity to cause the cutters n to completely pulverize the ground which has previously been dug up by the digging-teeth h. The loose ends of the pendent arms K, which form the bearings for the pulverizing-cylinders, connect by ropes or chains o with a windlass, p. This windlass has its bearings in the upper ends of the arms a, which carry the smoothing-roller B, as previously described, and it is furnished with a ratchet-wheel and pawl, or any other equivalent device, so that it can be arrested in the desired position. By turning the windlass in the proper direction the pulverizing-cylinder can be raised from or lowered to the ground, and the depth to

which the cutters n penetrate regulated at pleasure.

If steam-power is used for propelling this digging-machine, the boiler and engine are placed on the frame, and the piston is connected to the disks D by gear-wheels or any other suitable means, and in this case the teeth h act in the double capacity of digging-teeth and propelling-teeth.

Our machine can be used as a traction-engine by removing the tooth-bars h, and by elevating the disks D' clear off from the ground. A belt applied to one of said disks may be used for the purpose of transmitting the power of the steam-engine to thrashing or other working machines.

When the tooth-bars are removed this machine may be used for all the purposes of a locomotive or stationary engine needed on the farm, which constitutes a decided improvement of our digging-machine over all others.

Having thus fully described our invention, what we claim as new, and desire to secure by Letters Patent, is—

The arrangement and combination of the windlass l, levers G, digging-cylinder D, with teeth h, attached to fixed or oscillating bars, pendent arms k, pulverizing-cylinder J, and windlass p, all constructed and operating in the manner and for the purpose set forth.

W. F. QUINBY.
GEORGE G. LOBDELL.
